UNITED STATES PATENT OFFICE.

WALTER F. HEROLD, OF NEWARK, NEW JERSEY, ASSIGNOR TO THE BASSICK COMPANY, OF BRIDGEPORT, CONNECTICUT, A CORPORATION OF CONNECTICUT.

CASTER.

Application filed April 28, 1924. Serial No. 709,343.

To all whom it may concern:

Be it known that I, WALTER F. HEROLD, a citizen of the United States, and resident of Newark, in the county of Essex and State 5 of New Jersey, have invented certain new and useful Improvements in Casters, of which the following is a specification.

The invention relates to improvements in casters, and particularly to improvements in 10 the caster horn. An object of the invention is the provision of a horn so shaped and reinforced as to resist the stresses to which the same is subjected in use more effectively than other horns of similar thickness of 15 metal with which I am familiar.

It is common practice to press up the metal of the transverse top portion of the horn to form a circular reinforcement through the center of which extends the 20 opening in which the lower end of the caster pintle is riveted. This circular domed or arched reinforcement forms the seat upon which rests a shoulder on the pintle or washer surrounding the pintle through 25 which the weight carried by the caster is transmitted, through the horn, to the caster wheel or other rolling member.

The circular dome was, of course, provided in an effort to reinforce the top portion 30 of the horn against bending or deformation of the same because of the weight transmitted to the center thereof, as well as to withstand the stresses due to forces tending to tilt the pintle. Other attempts 35 to reinforce the top portion of the horn have aimed to stiffen the front or rear edges, as by turning downwardly the front or rear edges, or both, of the horn top portion or yoke.

40 I have determined that none of these devices served to resist the stresses imposed upon the horn yoke in the most effective manner, and have found that the desired object may be accomplished by a simple 45 modification of the previously used central doming of the yoke. Such doming is advantageous in stiffening the central portion of the yoke. Experience shows however that yokes having a central circular dome 50 are liable to downward deformation along the front edges of the yoke, that is, the edge of the yoke located between the planes of the caster wheel and pintle axes. I have found that this is due to forces acting 55 tangentially to the circular boss or dome of

the yoke. If, however, the front edge only of the yoke is stiffened, the yoke is liable to deformation between the pintle opening and the stiffened edge.

I overcome these difficulties most effectively by making use of the dome or boss about the pintle, but extending the same forwardly so as to interpose arched metal in the line of the tangential forces referred to. This may be accomplished, for example, by extending the circular boss forwardly, to make a D shape, with the base of the D parallel and adjacent to the front edge of the yoke.

The invention consists in the improved 59 caster horn referred to and in the various combinations of parts and details of construction thereof, all as will be more fully set forth in the following specification in connection with the preferred embodiment 70 thereof, and be particularly pointed out in the appended claims.

In order that the invention may be more clearly understood attention is hereby directed to the accompanying drawings forming part of this application and illustrating one embodiment of the invention. In 81 the drawings—

Fig. 1 represents a side elevation of a 85 caster horn, the arms of which carry a caster wheel and the yoke or top portion of which has a caster pintle secured thereto;

Fig. 2 is an enlarged partial longitudinal section taken through the caster horn with the pintle shown in side elevation, this section being taken on line 2—2 of Fig. 3;

Fig. 3 is a top plan view of the caster 95 horn and pintle on a further enlarged scale, this view also showing the manner in which failure might occur in a horn having a circular dome or boss thereon, and

Fig. 4 is a transverse vertical section taken on line 4—4 of Fig. 2.

Referring to the drawings, the caster horn comprises the arms 1, 1, which extend downwardly from the yoke or transverse top portion 2. The caster wheel 3 is rotatably supported on the usual axle 4 carried by the arms 1. The pintle 5 is secured on the yoke or top horn portion 2, in usual fashion as by having a portion 6 thereof extend through the centrally located pintle opening in the yoke of the horn, the bottom end of the pintle being upset, as shown at 8, beneath the yoke of the horn.

The yoke or transverse top portion of the horn is provided with an upwardly extending reinforcement 9, which, as shown, is approximately D-shaped, the base of the D being formed by the front edge 10 of the reinforcement, adjacent to the front edge 11 of the yoke, that is to say, the transverse edge of the yoke nearest to the axis of the caster wheel. The reinforcement is preferably domed or arched upwardly to a comparatively small height, by pressing the metal of the yoke upwardly in the form indicated, the horn being formed of sheet metal, as is usual. With this construction the dome or reinforcement 9 has a semi-circular rear portion 12 and a forwardly extending portion having side edges 13, 13, which connect the semi-circular rear portion 12 with the front edge 10 of the D reinforcement. The horn is arched at the junctions of the yoke 2 and arms 1, as is usual, the arched junctions being indicated at 14 in Fig. 4. The side edges 13 of the D-shaped reinforcement preferably extend forwardly over the arches 14 of the horn, these side edges 13 being more or less parallel to the planes in which the arms 1 of the horn are located.

In the prior construction referred to, in which a circular dome or boss was provided on the yoke, the forwardly extending sides 13 joined by the front edge 10 of the reinforcement are, of course, not present, such circular boss being made up of the semi-circular portion 12 of the present boss and the front semi-circular portion 15 indicated in dash and dotted lines on Fig. 3. With any caster of the character referred to the weight borne by the furniture leg is transmitted from the pintle to the yoke, and thence to the arms of the horn, and thence to the caster wheel. The pintle may be provided with an annular shoulder 16 which rests on the boss or dome of the yoke and transmits the weight of the leg to the yoke.

With the prior circular dome on the yoke the crushing force thus transmitted to the yoke acted along the lines of least resistance in the yoke to cause bending thereof, when the applied force was greater than the capacity of the yoke to withstand without deformation. I have determined experimentally that this crushing force was exerted along the tangential lines indicated in dot and dash in Fig. 3 at 17, 17, these lines being tangential to the circular boss or dome and converging so as to meet at a point 18 forwardly of the front edge of the yoke, over the caster wheel. These lines of stress are tangential to the boss or reinforcement because of the fact that the arched metal of the reinforcement stiffens this part of the yoke, and they are inwardly directed at angles as indicated, because of the fact that the arched junctions 14 between the yoke

and arms of the horn stiffen the horn at such junctions and cause the yoke to deform along lines which are spaced inwardly from these arched portions 14. The lines of stress referred to extend forwardly, that is towards the caster wheel, because of the fact that the force must be transmitted forwardly from the pintle to the axis of the wheel, and also because of the fact that the axis of the wheel being in a different vertical plane from that of the axis of the pintle, the downward force at the axis of the pintle and the corresponding upward reaction at the axis of the wheel cause a tilting movement which tends to tilt the pintle forwardly. This latter action is accentuated when the wheel strikes against an obstruction such as the edge of a carpet, in moving the furniture. The most violent strain to which the caster horn may be put, however, is caused by dropping the furniture, when it has been lifted, in which case the force tending to deform the front edge of the yoke of the horn may be very severe.

With the improved construction described herein the action referred to is to a very great extent prevented by the interposition of reinforcing metal along the lines 17, 17, this reinforcing metal being provided by the corner portions 19, 19, of the D-reinforcement (Fig. 3), these corner portions comprising domed or arched portions of the upwardly pressed dome 9. Accordingly, the front edge of the yoke cannot be bent downwardly with my improved construction to any perceptible extent by a force which would bend downwardly on a considerable curve, the forward edge of the yoke in the prior construction having the circular domed boss.

With the improved construction any forwardly directed lines of force tangential to the portion 9 of the boss would extend alongside the edges 13 of the boss which extend over or lead into the arched portions 14 of the horn. These arches 14 of the horn constitute, of course, stiffening portions of the construction, and the domed reinforcement surrounding the pintle opening in the yoke is also a stiffening portion of the construction. It is not necessary, according to the data obtained by me, to stiffen the rear edge of the yoke in the same manner, the circular portion 9 of the boss surrounding the pintle opening at the rear being sufficient for the purpose.

What I claim is:

1. In a caster, a horn having a transverse top portion and forwardly and downwardly extending arms, said top portion having an upwardly-extending reinforcement of substantially D shape, with the base thereof adjacent and parallel to the front edge of said top portion, said reinforcement having a pintle opening therethrough.

2. In a caster, a horn having a transverse top portion and forwardly and downwardly extending arms, the horn being arched at the junctions of the top portion and arms, 5 and the top portion having an upwardly extending reinforcement with a pintle opening extending therethrough, said reinforcement extending around the pintle opening 35 at the rear, and having portions at the sides of the pintle opening extending forwardly beyond the same, positioned in the path of all forwardly extending bending stresses at the sides of said rearward portion other 40 than those directed solely into the arched junctions between the horn top and arms.
3. In a caster, a horn of pressed metal having a transverse top portion and forwardly and downwardly extending arms, 15 the horn being arched at the junctions of the top portion and arms, and the top portion having a portion thereof pressed upwardly to form domed reinforcement with a pintle opening extending there- 45 through, said reinforcement extending about the pintle opening at the rear, and having side edge portions extending forwardly at the sides of the pintle opening, 50 adjacent to the arched edge portions of said 55 horn top and substantially parallel therewith, said side edge portions of said reinforcement being connected by a transverse front portion in front of the pintle opening.
4. In a caster, a horn having a transverse top portion and forwardly and downwardly extending arms, the horn being arched at 20 the junctions of the top portion and arms, 25
- 30

In testimony whereof I have signed my 60 name to this specification.

WALTER F. HEROLD.
